UNITED STATES PATENT OFFICE

2,049,143

PHASE MODULATION

George L. Usselman, Port Jefferson, N. Y., assignor to Radio Corporation of America, a corporation of Delaware

Application April 1, 1932, Serial No. 602,487

15 Claims. (Cl. 179—171)

This invention relates to a method of and means for impressing phase modulations on radio waves or oscillations to be transmitted, and in particular to an improved method of and 5 means for accomplishing phase modulation by the use of modulator tubes having output, as well as input, electrodes connected in push-pull relation.

I have found that for reasons possibly not 10 fully comprehended at the present time phase modulated high frequency carriers are less subject to fading effects than the same carrier modulated otherwise. Further, that satisfactory transmission of short waves which are phase 15 modulated can be carried on over distances heretofore impossible with the use of short waves modulated in amplitude or frequency.

Since phase modulated waves are less subject 20 to the effects of fading than the same waves modulated otherwise and since phase modulated short waves can be transmitted over distances which cannot be covered by waves modulated otherwise, the practical application of the same is of the greater importance. For example, the use of 25 phase modulated signals in diversity reception enhances materially the quality of said reception.

The primary object of this invention is to provide an improved modulation method and system especially applicable to situations wherein a 30 two line balanced input and two line balanced output is required.

An advantage of a push-pull phase modulator as disclosed in the present invention is that neutralizing of the plate to grid capacities of the 35 amplifying modulator may be accomplished more satisfactorily than it can be done in phase modulators known heretofore in the art whether a single tube per stage is used or symmetrical tubes are used.

40 Briefly the above objects are attained in accordance with the present invention by the supplying of excitation voltages from a suitable oscillator to the grids of two modulator tubes through a phase changing device connected in series with each grid. In this arrangement the anodes of the two modulator tubes are connected to a common oscillating tank circuit. This oscillating tank circuit can function at only one frequency and phase at any given instant but the 45 phase of oscillations may be shifted from time to time by giving one tube more power input than is given to the other tube. This is accomplished by changing the bias to the grids of the modulator tubes. The phase shift in the modulator tubes, as accomplished above, changes or modu-

lates the phase of the output frequency of the transmitter. In phase modulated transmitters constructed in accordance with the present invention the frequency and the power output remain constant but the phase of the energy is advanced or retarded relative to a normal constant frequency about an average phase angle. The rate at which the phase is advanced or retarded depends upon the frequency of the modulating potentials. The amount of phase advance 5 or retardation will depend upon the amplitude of the modulating potentials and also upon the amount of fixed phase shift caused by the phase changing devices in the grid circuit.

The novel features of the invention have been 10 pointed out with particularity in the claims appended hereto. The method involved, the nature of the circuit, the operation thereof, and the numerous advantages flowing therefrom will be better understood from the following detailed 15 description thereof and therefrom when read in connection with the attached drawing in which:

Figure 1 illustrates the basic idea of the present invention; while

Figure 2 shows a modification of the arrangement of Figure 1.

Referring to Figure 1, A is a balanced type constant frequency oscillator of any known type in use today, as, for example a crystal controlled oscillator of the type disclosed in Hansell's 30 United States application Serial No. 540,310, filed May 27, 1931, or any other oscillator in use by radio engineers today, or a long line controlled oscillator such as disclosed by James L. Finch and James W. Conklin in their United States 35 application Serial No. 363,660, filed May 16, 1929, or any other long line frequency control generator known to radio engineers. The lines P and Q connect the oscillator output to a tuned grid tank circuit H by way of capacities 1 and 2 respectively. The lines P and Q should be of substantially equal electrical length and similar in other characteristics relative to each other, to ground, etc., in order that oscillations of substantially equal amplitude reach the tank circuit 45 H over each line from the generator A. The tank circuit H comprises a symmetrically tapped inductance 3 and variable tuning capacity 4. The center point of the tank circuit 3 is grounded through a blocking condenser W as shown. One 50 terminal of the tank circuit H is connected through a phase retarding means in the form of an inductance I to the grid 6 of thermionic modulator tube 7, while the other terminal of the inductance 3 of circuit H is connected through 55

a phase advancing means in the form of a capacity **J** to the grid **8** of a thermionic modulator tube **10**. The end of phase retarding inductance **I**, adjacent the grid **6**, is also connected to a resistance **R₁**, the other terminal of **R₁** is grounded for radio frequency by means of a blocking condenser **M** connecting the terminal of resistance **R₁** to the cathode **12** of tube **7**. The terminal of the phase advancing capacity **J** adjacent the grid **8** is also connected to one terminal of resistance **R₂**, the other terminal of **R₂** is connected by means of radio frequency by-passing condenser **N** to the cathode **14** of tube **10**. The low potential ends of resistors **R₁** and **R₂** are also connected in phase opposition to the terminals of a tapped secondary winding **16** of transformer **T**, the primary winding **18** of which is connected to an audio frequency modulating source **B** as shown. The cathode electrodes **12** and **14** of modulator tubes **7** and **10** respectively are connected to the battery or power source **20** as shown. A constant direct current biasing potential is applied through the secondary winding **16** and resistances **R₁**, **R₂** to the control electrodes **6** and **8** of modulator tubes **7** and **10** respectively by means of a connection **19** between the negative terminal of the source **20** and the center point on the secondary winding **16** of transformer **T**.

A tank circuit **22**, comprising a capacity **21** and inductance **23**, is tuned to normally oscillate at the frequency of the wave or oscillations to be modulated. The anodes **24**, **26** of modulator tubes **7** and **10** respectively are connected in phase opposition. This is accomplished by connecting the anodes **24** and **26**, as shown, to opposite ends of the oscillation circuit **22**. The center point of the inductance **23** is connected to the positive terminal of the source **20** so that a charging potential is applied from the source **20** to the anodes **24** and **26** respectively. Radio frequency oscillations are shunted around the source **20** from the filament circuit by way of a radio frequency by-pass condenser **27** connected, as shown in parallel with that portion of the source **20** included in the anode cathode circuit of the modulator tubes **7** and **10** respectively. Radio frequency oscillations appearing in the tank circuit **22** are prevented from passing through the source **20** by means of a capacity **27**. The potentials appearing on the anode **24** of modulator tube **7** are prevented from reacting on the grid electrode of tube **7** by means of a neutralizing capacity **K** connected between the anode **26** and the grid **6** as shown, while the potential oscillations appearing on the anode **26** of modulator tube **10** are prevented from reacting on the control electrode **8** of modulator tube **10** by means of a neutralizing capacity **L** connected between the anode **24** and the control electrode **8**.

The phase modulated oscillations appearing in the tank circuit **22** may be utilized in any manner. For example, they may be fed to an amplifier and/or frequency multiplier **F** by way of capacities **U** and **V** in the balanced lines connected to the output of the tank circuit **C**. The frequency multiplier may be of any type, as, for example, as shown in Hansell, United States Patent No. 1,878,308; or Green, United States Patent No. 1,878,309; or any other frequency multiplier known to radio engineers. In general, pure phase modulation is accomplished by this arrangement as disclosed. However, in the event that there has been some amplitude modulation taking place, the balanced lines, including the condens-

ers **U** and **V** may be caused to feed the energy to the amplifier and/or multiplier **F** by way of an amplitude limiter device **D**. Since this amplitude limiter device **D** and amplifier or frequency multiplier **F** per se form no part of the present invention, a detailed description thereof is thought unnecessary here. 5

In pointing out the operation of the device, it will first be assumed that oscillator **A** is supplying power at constant frequency to the input tank circuit **H**. This power is supplied to the grid tank circuit **H**, through the balanced lines **1** and **2**, and blocking condensers **P** and **Q**. Oscillations will be set upon in tank circuit **H**, the tuning or response of which is determined by inductance **3** and capacity **4**. Excitation voltage at constant frequency will be supplied from the tank circuit **H** through inductance **I** and condenser **J** to the grids **6** and **8** respectively of modulator tubes **7** and **10** respectively in substantial phase opposition or in push-pull fashion. However, the phase of the voltage excitation applied to the grid **6** of modulator tube **7** will be retarded to some extent by the inductance **I**, while the phase of the voltage excitation applied to the grid **8** of modulator tube **10** will be advanced to some extent by the capacity **J**. The amount of retardation and advancement in the phase of the excitation applied to the grids of these tubes may be changed and will depend upon the retarding or inductive value given to the inductance **I** and the advancing or capacitive value given to the condenser **J**, and also on the value of the resistance of resistors **R₁** and **R₂** respectively. 20 25 30 35

The impedance in each side of the grid circuit **H** should be kept balanced, then if both modulator tubes **7** and **10** have the same direct current bias, which is the case when no modulation energy is being supplied from **B**, the power supplied by each modulator tube to the tuned tank circuit **22** will be equal and the potential oscillations in circuit **22** will have a constant phase which will coincide with the average phase position of the excitation voltage, keeping in mind that the oscillations in circuit **C** are of constant frequency. 40 45

Now, if we assume that audio frequency modulations are produced in **B** and applied through the transformer **T** to the control electrodes of **7** and **10** respectively, the bias applied to the electrodes **6** and **8** of tubes **7** and **10** respectively will vary 50 in phase opposition and the tube having the lower bias at any particular instance will supply the most power to the tuned tank circuit **22**. Since the excitation to the grids **6** and **8** of the two modulator tubes **7** and **10** respectively has a phase difference the power supplied to the tank circuit **22**, by the anodes **24**, **26** of the two modulator tubes **7** and **10**, will have a phase difference. The phase of the oscillations appearing in circuit **22** will change or approach that of the tube having 60 the lower grid bias and therefore supplying the more power. The amount of phase change in the circuit **22** will be substantially proportional to the difference in power delivered by the tubes **7** and **10** to the circuit **22**. It is obvious, however, that there may be no greater phase shift in the tank circuit **22** than there is phase difference of excitation applied to the grids of tubes **7** and **10** respectively. 65

From the above description it can be seen that 70 variations in audio frequency amplitude applied from source **B** to the control electrodes of the modulator tubes **7** and **10** respectively will produce corresponding variations in phase of the 75

normal constant frequency oscillations in circuit 22.

One advantage of the circuit as disclosed above is that the tubes, being connected in push-pull, 5 may be readily neutralized by means of the capacities K and L.

This circuit also provides all of the advantages attendant on the use of push-pull tubes since the plates or anodes are connected so that they 10 deliver power in push-pull fashion and in phase opposition.

This circuit also readily lends itself to grid neutralization and to other schemes of balancing applied to radio frequency circuits.

15 In Figure 2 is shown a modification of the arrangement of Figure 1. In this arrangement, which is otherwise similar to the arrangement shown in Figure 1, screen grid tubes are used, thereby eliminating the necessity of neutralizing 20 the inter-electrode capacity as was the case in the arrangement of Fig. 1. This arrangement also differs from the arrangement shown in Figure 1 in that the audio frequency modulation is introduced, as shown, on the screen grid electrodes 25 of the modulator tubes instead of on the control grid electrodes, as was the case in Figure 1. Furthermore, the modulating potentials of the present arrangement are amplified before being used to phase modulate the carrier.

30 The oscillation generator A of Figure 2, and the means by which oscillations at a carrier frequency, the phase of which are alternately advanced or retarded an amount determined by the inductance I and capacity J, are caused to appear in the 35 tank circuit 22, is the same as the corresponding elements and means of the arrangement of Figure 1. The means by which the phase modulations are impressed on the carrier in the arrangement of Figure 2, however, differ.

40 In Figure 2 the tubes 7 and 10 are of the screen grid type and the modulating frequencies are impressed on the screen grid electrodes 36 and 37 respectively to thereby vary the conductivity of the tubes 7 and 10 respectively, and 45 in that manner modulate the phase of the carrier oscillations at a rate determined by the frequency of the modulating potentials and by an amount determined by the amplitude of the modulating potentials limited, of course, by the 50 alternating phase advancing and retarding effect imparted to the carrier frequency oscillations by the inductance I and capacity J. The modulating potentials are applied to screen grid electrodes 36, 37 from the anodes 34, 35 respectively 55 of a pair of thermionic tubes 28, 29 having their anodes connected in parallel through resistances R₃, R₄ to a point on a potentiometer 38 in parallel with source 20. The modulating potentials obtained from the source B are impressed on 60 the transformer T and from the secondary winding 16 of the transformer T to the control electrodes 32, 33 of tubes 28, 29 respectively. These 65 modulating potentials, applied in phase opposition to the control electrodes 32 and 33, are repeated and amplified in the tubes 28 and 29 respectively. The screen grid electrodes 36, 37 of tubes 7 and 10 respectively are supplied with 70 charging potentials by way of resistances R₃, R₄ respectively, which also supply charging potential for the anodes 34, 35 of the tubes 28 and 29 respectively. Biasing potential for the tubes 28 and 29 is supplied by way of a lead 19 connected with the source 20 and the midpoint of winding 16. Biasing potential for the grid electrodes of 75 the tubes 7 and 10 respectively is supplied by

way of a lead 19' connecting the resistances R₁, R₂ to a point on the potentiometer 39 connected in parallel with the source 20.

In operation the modulating frequency potentials are applied in phase opposition to the control electrodes 32 and 33, of tubes 28 and 29 respectively. These tubes become alternately more conducting and less conducting at a degree and frequency determined by the intensity and frequency of the modulating potentials. When 10 tube 28 becomes more conductive the anode circuit thereof, including the resistance R₃, draws more current, which causes an increase in voltage drop across resistor R₃. The voltage drop across a resistor opposes the potential which 15 causes the current to flow, so that an increase in current through resistor R₃ decreases the positive potential on the screen grid electrode 37. This potential variation applied to screen grid 20 37 governs the amount of energy supplied to the tank circuit 22 connected with the anode 26 of tube 10. In this case the energy supplied by tube 10 is reduced. At the same time, since the modulating potentials are applied in phase opposition to the control electrodes of tubes 28 and 25 29, tube 29 is rendered less conductive so that less current flows in resistance R₄. This causes less voltage drop in resistance R₄, which results in an increase of positive potential applied to the 30 screen grid electrode 36 of tube 7, thereby causing the anode 24 of tube 7 to draw more current and to supply more energy to the tank circuit 22. Since the energy in tank circuit 22 is mostly from tube 7, the phase of the energy supplied from tube 7 to a great extent determines the 35 phase of the energy in the tank circuit. When the modulating potentials applied to the secondary windings 16 reverse in sign the reversed operation takes place. Tube 29 now draws more current while tube 28 draws less current so that 40 the positive potential applied to the screen grid electrode 36 decreases and the positive potential applied to the screen grid electrode 37 increases. Tube 7 now becomes less conductive and tube 45 10 becomes more conductive. The energy in the tank circuit 22, therefore, is mostly energy supplied from the anode 26 of tube 10. For that reason the phase of the energy in tank circuit 22, at this particular instant, is determined to a great extent by the phase of the energy supplied from the tube 10. In this manner the 50 high frequency oscillations supplied from A, through high frequency phase shifting means I and J to tubes 7 and 10 respectively, are modulated in phase at a degree and rate determined 55 by the intensity and frequency of the modulating potentials produced in B. As will be obvious, the object of this arrangement, except as otherwise indicated above, is the same as the object of the arrangement shown in Figure 1.

The present arrangement includes all of the advantages of the arrangement of Figure 1 and, in addition thereto, eliminates the necessity of the use of neutralizing capacities to prevent reaction between input and output circuits of the 65 modulator tubes.

The amount of desired sideband energy and the amount of undesired sideband energy, resulting from the phase modulation of the carrier at signal frequency accomplished in the devices 70 of Figures 1 and 2, depends in part on the amplitude of the carrier or of the modulating potentials. By regulating the amplitude of either the carrier or the modulating potentials, the amount of the undesired sideband or components 75

may be diminished or increased at will. By regulating the amplitude of the modulating potentials at the source B in either of the arrangements shown in Figure 1 or 2, or by adjusting 5 the lead 19 along the potentiometer 39 of Figure 2 to control the amplification of the modulation frequency amplifiers 28 and 29, the amplitude of the modulating potentials acting on the impedances of tubes 7 and 10 may be regulated, 10 thereby controlling the amount of desired and undesired sideband energy appearing in the circuit 22. The amplitude components and other undesired energy of the same nature may be removed in the unit D. The phase modulation 15 components may be increased in degree by multiplying the frequency of the phase modulated energy in F.

Having thus described my invention and the operation thereof, what I claim is:

- 20 1. Transmitting means comprising a source of oscillations, a pair of thermionic tubes of the screen grid type, connections between said source and the control electrodes of said tubes for applying oscillations in phase opposition to the control electrodes of said tubes, means for phase modulating said oscillations comprising phase shifting means in each of said connections, a tank circuit connecting the anodes of said tubes in push-pull relation, a source of modulating potentials, and means for impressing the modulating potentials in phase opposition on the screen grid electrodes of said tubes.
- 25 2. Means for amplifying and phase modulating high frequency energy comprising, a pair of thermionic tubes of the screen grid type having their input electrodes energized in phase opposition by carrier frequency potentials, means for retarding the phase of the carrier frequency potentials applied to one of said grid electrodes, and means 30 for advancing the phase of the carrier frequency potentials applied to the other of said grid electrodes, a tank circuit connected between the anodes of said tubes, and means for impressing modulating potentials in phase opposition on the screen grid electrodes of said tubes.
- 35 3. An arrangement as claimed in claim 2 in which said last named means includes amplifying means.

- 40 4. Means for impressing phase modulations at signal frequency on high frequency oscillations comprising, a pair of thermionic tubes of the screen grid type, means for impressing high frequency oscillations in opposition on the control electrodes of said tubes, phase shifting means 45 interposed between the control electrodes of one of said tubes and said impressing means, a load circuit connected between the anodes of said tubes, a pair of thermionic amplifiers, means for impressing modulating frequencies on the control electrodes of said amplifiers in phase opposition, a connection between the anode of each of said amplifiers and the screen grid in one of said screen grid tubes, and means for connecting the anodes of said last named tubes to a source 50 of potential.

- 55 5. A means for producing and phase modulating high frequency oscillations including the combination of a constant frequency oscillator, a push-pull modulator having a tank circuit 60 which may be connected with the input electrodes thereof and a tank circuit connected with the output electrodes thereof, a balanced line connecting said oscillator to said input tank circuit, phase shifting means of different characteristics 65 connected between the control electrode of each

of said modulator tubes and a terminal of said input tank circuit, means for applying direct current biasing potential to the control electrodes of each of said modulator tubes, and a balanced means for super-imposing modulating potentials 5 in phase opposition on the direct current potential applied to said control electrodes.

6. Transmitting means comprising the combination of a constant frequency oscillation generator, a pair of modulator tubes having an input 10 tuned tank circuit connected in push-pull relation with the control electrodes thereof and a tank circuit connected in push-pull relation with the output electrodes thereof, means for connecting said oscillation generator to said input 15 tank circuit, phase shifting means of different characteristics connected between the control electrode of each of said modulator tubes and a terminal of said input tank circuit, means for applying direct current biasing potential to the 20 control electrodes of each of said modulator tubes, and a balanced means for differentially applying modulating potentials to the control electrodes of said tubes.

7. The combination with a source of carrier 25 frequency oscillations of a phase modulator comprising, a pair of thermionic tubes having their control grids connected by reactances of different electrical characteristic to said source of oscillations, their anodes connected in push-pull 30 relation by an output circuit and their anode to control grid capacities neutralized by variable capacities, a source of modulating potentials connected by way of thermionic repeaters in phase opposition to the impedances of the tubes in said 35 modulator whereby carrier oscillations from said source are modulated in phase at signal frequency and inadvertently modulated in amplitude, an amplitude limiter connected with the output circuit of said tubes whereby the amplitude modulation inadvertently accomplished is removed from the modulated energy, and a frequency multiplier coupled with said limiter to increase the degree of phase modulation accomplished. 45

8. The combination of an oscillator and a modulator stage comprising, a pair of thermionic tubes each having control grid and anode electrodes, said control grids and said anodes being coupled in push-pull relation by input and output 50 circuits respectively, each of which circuits include an inductance, a balanced line connecting the oscillator in parallel with a portion of the inductance in said input circuit, phase shifting reactances of different character in said 55 input circuit connected with the control grid of each of said tubes in said modulator stage, a balanced line connecting a portion of the inductance in the output circuit of said tubes to said load circuit, and means for phase modulating 60 the oscillations from said oscillator comprising means for applying modulating potentials in phase opposition to similar electrodes in each of said tubes.

9. Transmitting means comprising the combination of, a constant frequency oscillation generator, a pair of modulator tubes each having control grid and anode electrodes, an input circuit, phase shifting reactances of different character connecting the control grids of said modulator 70 tubes in push-pull relation by way of said input circuit, an output circuit connecting the anodes of said tubes in push-pull relation, a line connecting said oscillation generator in parallel with said input circuit, a circuit for applying biasing 75

potentials to the control grid electrodes of each of said tubes and energizing potentials to the anodes of each of said tubes, and means for phase modulating the oscillations from said oscillation generator comprising a balanced means for differentially applying modulating potentials to like electrodes in each of said tubes.

10. A phase modulating means comprising, a pair of thermionic tubes each having anode and control electrodes, a tank circuit adapted to be energized by carrier frequency oscillations, a reactance connecting one terminal of said tank circuit to the control electrodes of one of said tubes, a reactance connecting the other terminal of said tank circuit to the control electrode of the other of said tubes to excite the same in out of phase relation, a circuit connecting the anodes of said tubes in push-pull relation, a source of modulating potentials, and a circuit for applying said potentials from said last named source in phase opposition to like electrodes in each of said tubes.

11. The combination of a constant frequency oscillator, a modulator stage of the thermionic tube type having input electrodes and output electrodes connected in push-pull circuits each of which includes an inductance, and a load circuit, a balanced line connecting said oscillator to points on the inductance connected with the input electrodes of said tubes, a balanced line connecting points on the inductance connected with the output electrodes of said modulator tubes to said load circuit, phase shifting means connected with the input electrode of each of said modulator tubes, said phase shifting means being of different character, a source of modulating potentials, and a circuit for applying modulating potentials from said source in phase opposition to like electrodes in each of said tubes.

12. The combination of a constant frequency oscillator, a modulator stage including, thermionic tubes connected in push-pull relation by input and output circuits each circuit including an inductance, and a load circuit, a balanced line connecting said oscillator to points on the inductance in the input circuit of said modulator stage, a balanced line connecting points on the inductance in the output circuit of said modulator stage to said load circuit, an inductive reactance connected between the inductance in said input circuit and the input electrode of one of said tubes in said stage, a capacitive reactance connected between the inductance in said input circuit and the input electrode in the other of said tubes in said modulator stage, and a circuit for applying modulating voltages in phase opposition to the impedance between two electrodes of each tube in said modulator stage.

13. The combination of a constant frequency oscillator, a pair of thermionic tubes each having an anode, a cathode and a control electrode, reactances connecting said control electrodes and said anodes in push-pull circuits, a load circuit, a balanced line connecting said oscillator to the reactance connected with the control electrodes of said tubes, a connection between the electrical center of said last-named reactance and the cathodes of said tubes, a balanced line connecting the reactance between said anodes to said load circuit, a connection between the electrical center of said last-named reactance and the cathodes of said tubes, phase shifting reactances connected with the control electrode of each of said tubes, said phase shifting reactances being of different character, and a circuit for applying modulating voltages in phase opposition to like electrodes of each of said tubes.

14. Means for impressing phase modulations at signal frequency on high frequency oscillations comprising, a pair of thermionic tubes of the screen grid type, each having anode, cathode, control grid and screen grid electrodes, a circuit for impressing high frequency oscillations in phase opposition on the control grids of said tubes, phase shifting reactances interposed between the control grid of each of said tubes and a different point on said impressing circuit, a load circuit connected with the anodes of said tubes, a pair of thermionic amplifier tubes each having an anode and a control grid, circuits connected with the control grids of said amplifier tubes for impressing modulating potentials in phase opposition on the control grids of said amplifier tubes, and connections between the anode of one of said amplifier tubes and the screen grid in one of said screen grid tubes and between the anode of the other of said amplifier tubes and the screen in the other of said screen grid tubes.

15. In a phase modulating system, a pair of thermionic tubes each having a control grid and a cathode, a tank circuit adapted to be energized by high frequency oscillatory energy, an inductive reactance connecting one terminal of said tank circuit to the control grid of one of said tubes, a capacitive reactance connecting the other terminal of said tank circuit to the control grid of the other of said tubes, a connection between a point on said tank circuit and the cathodes of said tubes whereby said control grids are excited substantially in phase opposition by oscillatory energy in said tank circuit, and a source of modulating voltages connecting the control grids of said tubes in phase opposition.

GEORGE L. USSELMAN.
